UNITED STATES PATENT OFFICE.

LUTHER P. FRIESTEDT, OF CHICAGO, ILLINOIS.

SHEET-PILING.

SPECIFICATION forming part of Letters Patent No. 734,314, dated July 21, 1903.

Application filed October 9, 1902. Serial No. 126,498. (No model.)

To all whom it may concern:

Be it known that I, LUTHER P. FRIESTEDT, a citizen of the United States, residing at Chicago, in the county of Cook and State of Illinois, have invented certain new and useful Improvements in Sheet-Piling; and I do hereby declare the following to be a full, clear, and exact description of the invention, such as will enable others skilled in the art to which it applies to make and use the same.

This invention relates to sheet-piling, and has for its object to provide an improved metal beam differing somewhat from the beam-sections set forth in Letters Patent No. 707,837, dated August 26, 1902, and in another application filed contemporaneously herewith, Serial No. 126,497.

In the drawings, Figure 1 is a plan of a wall structure embodying the improved features; and Fig. 2 is an elevation and part section on line 2, Fig. 1, looking in the direction indicated by the arrow.

The beam-sections have the same alternate arrangement as that set forth in the patent referred to, the section A being set with the flange edges pointing outwardly and the section B set with its flanges pointing inwardly and having an interlocking engagement edgewise. In the present application the channel-beam A is formed with the integral additional flanges 3, which are turned outward at right angles with reference to the usual beam-flanges 4 and parallel with the web 5 of the beam. The flanges 3 overlap the corners 35 and a part of the web 6 of the two adjacent beam-sections B, as shown in Fig. 1.

The wings 7 of the companion angle-irons 8 are riveted to the back and adjacent to the corners of the beam-sections A, as at 9, the wings 10 lying parallel with the flanges 4 and providing a space *a* for the reception of the flanges of the beam-sections B in assembling and locking the parts together. This construction forms a very strong connection for the interlocking beam edges and exposes nothing but the beam-surfaces on the out-

side and where the greatest resistance is to be met, the angle-irons being all located in the inside.

The method of constructing the corner-sections is different from that described and shown heretofore. The corners here shown consist of the outside companion beams 11 and 12, which are substantially the two halves of a channel-beam A split longitudinally and then positioned to bring the web parts 13 at right angles to each other. In the inside corner so formed by the web parts is placed an angle-iron 14, solidly riveted to the half channel-sections. In this corner construction the angle-irons 8 are placed at right angles to each other in corresponding to the relative position of the companion half-sections 11 and 12, and rigidly secured thereto, the free wings 10 extending around in the usual position for the engagement of the flanges of the sections B, the additional flanges 15 on the half-sections overlapping the adjacent corners of the beam-sections B in the main lineal wall.

In Fig. 2 the beam-sections are shown as having been started into the earth in the operation of sinking a shaft.

Having thus described my invention, what I claim, and desire to secure by Letters Patent, is—

1. In sheet-piling, the combination with a beam-section of an edgewise-interlocking channel-beam provided with an additional flange extension starting at right angles from the edge of the usual flanges and running parallel with the web part and overlapping the respective corners of said beam-section and means for loosely retaining the beam-sections in their engaged position, substantially as set forth.

2. In sheet-piling, the combination with the beam-section A, provided on each edge with an additional flange extension lying parallel with the web part thereof, the joining interlocking sections B, overlapped by said flange extensions, and the angle-irons secured to

beams A and extending around on the outside of the flanges on beams B, substantially as set forth.

3. In a corner structure for sheet-piling, the combination with the companion half beam-sections turned at right angles with reference to each other, the corner angle-iron secured thereto and rigidly joining the half-sections and the angle-irons, secured to and extending

around the corners of the half-sections and overlapping the flanges on the joining section B, substantially as set forth.

In testimony whereof I affix my signature in presence of two witnesses.

LUTHER P. FRIESTEDT.
